MINING APPARATUS

Filed May 4, 1922

FIG. 1.

FIG. 2.

FIG. 3.

FIG. 4.

INVENTOR:
William E. Boudette,
by

Frank L. Lee

attorney.

UNITED STATES PATENT OFFICE.

WILLIAM E. BOUDETTE, OF CLAREMONT, NEW HAMPSHIRE, ASSIGNOR TO SULLIVAN MACHINERY COMPANY, A CORPORATION OF MASSACHUSETTS.

MINING APPARATUS.

Application filed May 4, 1922. Serial No. 558,448.

My invention relates to mining apparatus. It has for its object to provide an improved and simplified mining machine support whereby a mining machine may be supported above the bottom for movement relative to the bottom and whereupon the mining machine may be loaded, support and all, upon a truck for transport. A further object of my invention is to provide an improved support of the character set forth which is not only simple in construction and adapted to be manufactured at small expense while retaining the desired ruggedness of character necessary to its service, but which also is of a type permitting variations in height of the support to be conveniently obtained without materially increasing the cost.

In the accompanying drawings I have shown for purposes of illustration two embodiments which my invention may assume in practice.

In these drawings,—

Fig. 1 is a side elevation of a mining machine equipped with my improvement and loaded upon its truck.

Fig. 2 is a side elevation of one form of my improved support.

Fig. 3 is a transverse sectional view on line 3—3 of Fig. 2.

Fig. 4 is a similar transverse section of my improved construction adapted to use in a lower support.

In the accompanying drawings, I have shown for purposes of illustration a mining machine 1 of standard construction mounted on a truck 2 of similar standard construction and adapted to drive the truck wheels 3 through driving connections 4, 5, the mining machine herein being carried upon an improved machine support hereinafter described upon which the machine may be moved relative to the bottom or on which the machine may be loaded on to the truck, the machine when loaded on to the truck being latched into position thereon by means of a swinging latch 6 on the support engaging a latching plate 7 carried by the side of the truck.

In my improved construction a bottom engaging shoe or skid 8 is provided preferably having upturned front and rear ends 9 and slightly upturned sides 10 to permit a free universal movement of the bottom plate

on the mine bottom or relative to a truck. 55 As shown, a pair of angle members 11 is also disposed longitudinally beneath the bottom plate 12 of the mining machine at the desired distance apart and rigidly connected to the latter as by suitable screws 13, while 60 operatively connected between the depending portions of these angles 11 and the shoe 8 is an intermediate support herein in the form of another pair of angle irons 14 likewise longitudinally disposed and herein having a plurality of transverse bracing angles 15 disposed between the same, said angle members 14 and 15 being rigidly connected to the bottom engaging shoe 8 as by riveting. In the relatively high form of my improved 70 support shown in Fig. 3 upstanding intermediate plates 16 of suitable height and forming extensions of the angle irons are attached both to the depending portions of the angles 11 and to the upstanding portions 75 of the angles 14, by suitable rivets 17, while in the relatively low form of my improved support shown in Fig. 4 the depending portions of the angles 11 are directly connected to the upstanding portions of the angles 14 80 by similar rivets 18.

As a result of my improved construction, it will be evident that it is possible to provide a support for a mining machine which is not only of exceedingly simple and rugged construction, but which at the same time gives a high degree of flexibility as to height, the upper angles, for example, being simply spaced wider apart and adapted to be connected to the lower angles by 90 a connecting member of any desired height when a relatively high support is required, and adapted to be moved over closer together and fastened directly at any desired height to the lower angles when a lower height 95 is required. Attention is also directed to the fact that as shown in Fig. 3, my improved construction permits of the disposition of the latch 6 and its support within the lines of the machine support when a 100 high support is used.

While I have in this application specifically described two forms which my invention may assume in practice, it will be understood that these forms of the same are 105 shown for purposes of illustration and that the invention may be modified and embodied in various other forms without departing

from its spirit or the scope of the appended claims.

What I claim as new and desire to secure by Letters Patent is:

- 5 1. The combination with a mining machine, of means underlying the machine comprising a bottom plate, an intermediate support attached thereto, and a pair of longitudinally extending laterally spaced machine supporting members disposed above said intermediate support and rigidly connected thereto, said means constituting the sole support for the machine.
- 10 2. The combination with a mining machine, of means underlying the machine comprising a bottom plate, an intermediate support attached thereto including longitudinally disposed laterally spaced members, and a pair of longitudinally extending laterally spaced machine supporting members disposed above said intermediate support and rigidly connected thereto, said means constituting the sole support for the machine.
- 15 3. The combination with a mining machine, of means underlying the machine including a bottom plate, longitudinally extending angle irons attached thereto and having upstanding portions, and a pair of longitudinal machine supporting angle irons having depending portions supported by the upstanding portions of said first mentioned angle irons and having their remaining portions disposed parallel to said bottom plate, said means constituting the sole support for the machine.
- 20 4. The combination with a mining machine, of means underlying the machine including a bottom plate, longitudinally extending angle irons attached thereto and having upstanding portions, and a pair of longitudinal machine supporting angle irons having depending portions supported by the upstanding portions of said first mentioned angle irons and having the remaining portions disposed parallel to said bottom plate and projecting in the same direction as the remaining portions of said first mentioned angle irons, said means constituting the sole support for the machine.
- 25 5. The combination with a mining machine, of means underlying the machine including a bottom plate, longitudinally extending machine supporting angle irons attached thereto and having upstanding portions, a pair of longitudinal angle irons having depending portions supported by the upstanding portions of said first mentioned angle irons, and members rigidly bracing said first mentioned angle irons transversely, said means constituting the sole support for the machine.
- 30 6. The combination with a mining machine, of means underlying the machine including a bottom plate, longitudinally ex-

tending machine supporting angle irons attached thereto and having upstanding portions, a pair of longitudinal angle irons having depending portions supported by the upstanding portions of said first mentioned angle irons, and transversely disposed angle irons rigidly connected to said bottom plate and disposed between said first mentioned angle irons, said means constituting the sole support for the machine.

7. The combination with a mining machine having a bottom plate, of means underlying the machine comprising a bottom plate and an intermediate support, and a plurality of laterally spaced longitudinally extending machine supporting portions rigidly connected to the bottom plate of said mining machine and rigidly connected to said intermediate support, said means constituting the sole support for the machine.

8. The combination with a mining machine, of means underlying the machine comprising a bottom plate, longitudinally disposed intermediate supports attached thereto, each of the same being spaced from one edge of said plate, and a pair of longitudinally extending laterally spaced machine supporting members disposed above said intermediate supports and connected thereto and having lateral portions overlying the space mentioned, said means constituting the sole support for the machine.

9. The combination with a mining machine, of means underlying the machine comprising a bottom plate, longitudinally disposed intermediate supports attached thereto, certain parts of the same being spaced from said plate, a pair of longitudinally extending laterally spaced machine supporting members disposed above said intermediate supports and connected thereto, and mechanism carried by said plate and disposed in the space mentioned for locking the support on a transport truck, said means constituting the sole support for the machine.

10. The combination with a mining machine, of means underlying the machine comprising a bottom plate, longitudinally disposed intermediate supports attached thereto, certain parts of the same being spaced from said plate, a pair of longitudinally extending laterally spaced machine supporting members disposed above said intermediate supports and connected thereto, and mechanism including a pivoted latch carried by said plate and disposed in the space mentioned for locking the support on a transport truck, said means constituting the sole support for the machine.

11. A mining machine support comprising a bottom plate adapted slidably to engage a mine bottom, longitudinally extending laterally spaced angle members rigidly connected thereto, longitudinally extending

parallel plates rigidly secured to said angle members, and angle members rigidly secured to said first mentioned angle members by said plates and thereby to the bottom of the machine.

12. A mining machine support comprising a bottom plate adapted slidably to engage a mine bottom, longitudinally extending laterally spaced angle members rigidly connected thereto, longitudinally extending parallel plates rigidly secured to said angle members, angle members rigidly secured to said first mentioned angle members by said plates and thereby to the bottom of the machine, and transversely extending bracing

members rigidly secured to said bottom plate.

13. A mining machine support comprising a bottom plate having upturned sides and ends and adapted to freely slide on the mine bottom, angle members secured to said plate, angle members secured to the bottom of said machine, intermediate vertically disposed plates secured to said angle members respectively, and transversely extending bracing members rigidly secured to said bottom plate intermediate said first mentioned angle members.

In testimony whereof I affix my signature.

WILLIAM E. BOUDETTE.
